[57] CLAIM

The ornamental design for a connectable toppling toy,
as shown and described.

DESCRIPTION

FIG. 1 is a front perspective view of a connectable
toppling toy showing my new design;

FIG. 2 is a front elevational view thereof;

FIG. 3 is a rear elevational view thereof;

FIG. 4 is a top plan view thereof;

FIG. 5 is a left side elevational view thereof, the oppo-
site side being identical;

FIG. 6 is a bottom plan view thereof.
